UNITED STATES PATENT OFFICE

156,151

DESIGN FOR A FISHING ROD BUTT

Manuel J. Nunes, Oakland, Calif.

Application October 27, 1948, Serial No. 149,335

Term of patent 14 years

(Cl. D31—4)

To all whom it may concern:

Be it known that I, Manuel J. Nunes, a citizen of the United States and a resident of Oakland, county of Alameda, and State of California, have invented a new, original, and ornamental Design for a Fishing Rod Butt, of which the following is a specification, reference being had to the accompanying drawing, forming part thereof.

I claim:

The ornamental design for a fishing rod butt, substantially as shown.

MANUEL J. NUNES.
